BUFFING WHEEL

James V. Tullo, Bloomfield, N. J.

Application July 19, 1949; Serial No. 105,577

2 Claims. (Cl. 51—193)

1

My invention relates generally to ventilated buffing wheels, and specifically to ventilated buffing wheels that are capable of being constructed with very precise balance, thereby insuring their freedom from vibration and durability over long periods of operation.

It is among the objects of my invention to provide a buffing wheel which is ventilated, whereby the danger of the fabric catching on fire is substantially reduced, and the deterioration of the fabrics involved in the buffing wheel is greatly minimized, by reason of the cooler operation.

It is another object of my invention to provide a buffing wheel which is easy to construct and assemble.

Yet a further object of my invention is to provide a buffing wheel which may be operated at an extraordinarily high rate of speed, without the fabric being discharged therefrom, i. e., to provide a positive and sure anchorage for the fabric.

A still further object of my invention is to provide a buffing wheel which is constructed with uniform placement of the fabric so that the resulting buffing wheel is rather precisely balanced; thus trimming the buffing wheel to make it of uniform radius does not produce an unbalanced buffing wheel.

These objects and advantages, as well as many other objects and advantages, are achieved from the device illustrated in the drawings, in which:

Figure 1 is a front elevation view of the assemblage;

Figure 2 is a partial cross-section of the buffing wheel, taken on the line 2—2 in Figure 1;

Figure 3 is a partial cross-section of the unassembled buffing wheel showing the metal blanks before the fabric is attached thereto; and

Figure 4 is a partial top view of the metal blanks shown in Figure 3.

Referring now to the drawings in detail, my ventilated balanced buffing wheel is constructed as follows: A metal plate of perhaps twenty gauge metal is selected. This metal plate is formed into a body member 11 to which the fabric is later attached. A center hole 12 is punched out of the body member 11 to provide a means whereby the body member may be mounted on the hub or shaft of a buffing or polishing lathe. This center hole 12 is provided with a slight flange 13 to insure proper seating of the body member on the hub. Six or more radial slots 14, are also punched out of the body member 11. A shoulder 15 is then drawn. The outer margin of the body member 11 beyond the shoulder 15 is provided with a plurality of small holes 16 arranged circumfer-

entially around the shoulder 15, immediately adjacent thereto. The radial slots 14 extend to the shoulder 15 and provide a passage 20 from the slots through the shoulder.

5 A series of teeth 18 are cut in the outer edge of the body member. From the shoulder 15 to the outer edge of the teeth, the body member 11 is bent at an angle to the shoulder, thereby forming a flange 19. At the same time that this flange is formed, the teeth 18 are bent inwardly at an angle to the flange. A pair of body members 11 then take the form shown in Figure 3. These body members are placed with their inner faces together as shown in Figure 3 and are spot-welded together with their teeth arranged in offset or staggered fashion, as will appear in Figure 4. The buffing fabric 21 is now inserted between the teeth to a point approximately three thirty-seconds of an inch above the shoulder. It will be seen that this allows for the circulation of air through the holes 16 around the fabric. Pressure is applied to the flanges 19 and they are bent inwardly until the opposed flanges are parallel with each other. The flanges are thereby 10 disposed perpendicular to the shoulder and the teeth are disposed downward at an angle to the flange. It is preferred that a clearance of at least one-eighth of an inch still remains between the fabric and the shoulders to insure circulation of air at the point where the metal and fabric are clinched together.

15 The flanges are provided with a series of spacing ribs 22. When a multiple assemblage of buffing wheels is mounted on a hub, these ribs 22 serve to space the wheels from each other and permit circulation of air between them, thereby 20 insuring a cooler run.

Many changes may be made in the construction, selection, and arrangement of the various parts, all within the scope of the appended claims, without departing from the spirit of the invention.

I claim:

1. A buffing element comprising an annular, 45 laminated fabric buffing ring, a pair of opposed disks which constitute a support for the buffing ring having a peripheral groove receiving the inner edge of the buffing ring, each of the disks having a centrally located shaft receiving hub, a web member surrounding said hub, a shoulder at the outer periphery of the web, a narrow annular flange extending beyond the shoulder in a plane parallel to and offset from the web and having a plurality of teeth at the outer periphery thereof, a plurality of uniformly spaced holes 50 55

and a plurality of uniformly spaced outwardly extending ribs between the teeth and the shoulder, the web members having a plurality of concentrically arranged holes therethrough adjacent to and extending through the shoulders, the holes through each of the webs of the opposed disks being in registration with each other and the holes in the flanges and the teeth being in staggered relationship, the inner periphery of the buffering ring being spaced from the shoulders of the disks and the teeth on the flanges penetrating the fabric thereof adjacent the inner periphery from opposite sides in staggered offset relationship.

2. A buffering element comprising an annular laminated fabric buffering ring, a pair of opposed disks which constitute a support for the buffering ring having a peripheral groove receiving the inner edge of the buffering ring, each of the disks having a centrally located shaft receiving opening, a web member surrounding said opening, a shoulder at the outer periphery of the web, an annular flange extending beyond the shoulder in a plane parallel to and offset from the web and having a plurality of teeth at the outer periph-

ery thereof, a plurality of holes extending between the teeth and the shoulder, the web members having a plurality of concentrically arranged holes therethrough adjacent to and extending through the shoulders, the said holes through each of the webs of the opposed discs being in approximate registration with each other, and the teeth being in staggered relationship, the inner periphery of the buffering ring being spaced from the shoulders of the discs, and the teeth on the flanges penetrating the fabric thereof adjacent to the inner periphery from opposite sides in staggered offset relationship.

JAMES V. TULLO.
